UNITED STATES PATENT OFFICE.

WILLIAM EGLE, OF DETROIT, MICHIGAN.

HYDROCARBON BURNER.

Application filed March 29, 1920. Serial No. 369,811.

To all whom it may concern:

Be it known that I, WILLIAM EGLE, a citizen of the United States, residing at Detroit, in the county of Wayne and State of Michigan, have invented a new and useful 5 Hydrocarbon Burner, of which the following is a specification.

This invention relates to hydrocarbon burners and more particularly to burners 10 designed to use petroleum and like heavy hydrocarbon oils as fuel.

It is the object of the invention to provide a hydrocarbon burner having provision for preheating the fuel to decrease its viscosity and insure a more ready combustion, and further having means for mixing a 15 regulable quantity of air with the fuel prior to combustion, and means for delivering a regulable supply of air to support combustion 20 of the mixture.

A further feature of the invention is the regulation of the fuel discharge by means of the air which is mixed with the fuel prior to combustion.

25 In attaining these objects, the invention contemplates a liquid fuel nozzle disposed within an air passage to which air is delivered under pressure, said passage having a mixture outlet in line with the discharge 30 of said nozzle, and the latter being adjustable to and from said outlet so that the proportion of air in the mixture may be increased or decreased according as the nozzle is shifted from or toward said outlet. The 35 invention further contemplates a plurality of air tubes similarly inclined to discharge toward the point of combustion and adjustable in unison to or from said point.

A preferred embodiment of the invention 40 is hereinafter described and illustrated in the accompanying drawing, wherein,

Fig. 1 is a view of the improved burner in side elevation.

Fig. 2 is a longitudinal vertical sectional 45 view of the same.

In these views the reference character 1 designates a tubular air passage, and 2 is a hollow discharge head into which one end 50 of the member 1 is screw-threaded. Said head is formed with an outlet 3 from the passage 1, which outlet opens into a cup-shaped depression 4 in the exterior face of the head. Within the passage 1 there is centrally extended a liquid fuel nozzle 5, having the conical discharge head 6 formed

with the axial outlet 7, in alinement with the outlet 3, and also formed with a number of laterally opening discharge ports 8. The nozzle 5 is longitudinally adjustable to vary the spaced relation between the head 6 and outlet 3, being adapted for such adjustment by engagement with a slide bearing 9 suitably packed as indicated at 10 and carried by one end of a liquid fuel passage 11, which is secured to the passage 1 in alinement therewith. Within said passage 11 the member 1 has an actuating extension 12 formed by cutting said member along its axis and removing one of the halves thus produced, and by forming a rack of gear 70 teeth in the longitudinal edges of the remaining half. This rack is engaged by a pinion 13 mounted fast upon a stem 14 transversely journaled in the member 11 and projecting at one end exteriorly of said member 75 to receive an actuating handle 15. The passage 11 has a closed axial extension 16 to accommodate the rack member 12 in any of the various retracted positions of the nozzle carrying said member. Liquid fuel is delivered to the passage 11 from a pipe 17 having a portion 18 enclosed within a heating chamber formed by a passage 19 delivering air from the annular chamber 20 in the head 2 to the rear portion of the passage 1. 80 Air under pressure is supplied to said annular chamber through a pipe 21 communicating with said chamber preferably at a point diametrically opposite the outlet thereof. The head 2 provides a mounting 85 for a plurality of air tubes 22 similarly inclined to the axis of discharge of the burner, their discharge ends being convergent a short distance forward of the mixture outlet 3, and their rear ends being formed with 90 bell-mouthed air inlets 22^a slightly to the rear of the head 2. As a common means for adjusting said air tubes longitudinally in the head 2, a wing-nut 23 is engaged with a threaded portion of the member 1, and collars 24 respectively formed upon the rear 95 ends of said air tubes are extended into an annular slot 25 in the nut 23, said slot being suitably inclined to the axis of said nut to accommodate said collars. Thus when 100 the wing-nut is adjusted longitudinally upon the member 1, the air tubes are correspondingly shifted in unison along their respective axes.

The described burner is particularly de- 110

signed for burning the heavier liquid hydrocarbons, such as petroleum or crude oil, and by preheating both the fuel and the air which is commingled therewith a very satisfactory combustion of such fuels is secured. The head 2 becomes highly heated while the burner is in use, imparting a high temperature to the air flowing through the annular chamber 20. The air thus heated in flowing through the passage 19 exerts a pre-heating effect upon the liquid fuel which is being delivered through the pipe 19, so that the mixture which discharges from the outlet 3 is at a temperature requiring but little further elevation to reach the combustion point. The liquid fuel content of the mixture which discharges from the opening 3 is increased through approaching the nozzle head 6 to said opening, and decreased by retracting the nozzle so as to increase its distance from said opening. This regulation of the mixture follows from the described adjustment of the nozzle, for the reason that the body of air under pressure between the nozzle and outlet 3 opposes the discharge of liquid fuel and this opposition increases in proportion as the size of said body is increased through withdrawing the nozzle from said outlet. Combustion occurs closely adjacent the head 2, and is supported by the air drawn from the atmosphere into the bell-mouthed rear ends of the tubes 22 and delivered from the convergent ends of said tubes close to the point of combustion. The supply of air to the point of combustion thus effected is increased or decreased according as the tubes 22 are advanced or retracted through adjustment of the nut 23.

When both the nozzle 5 and the tubes 22 are properly adjusted, a thorough combustion results with a maximum of heat and minimum of smoke and soot. While designed primarily for use with heavy hydrocarbon fuels, the described burner is also applicable for use with almost any fluid hydrocarbon as fuel.

What I claim is:

1. A hydrocarbon burner, comprising a fluid fuel nozzle, a tubular air passage with in which said nozzle is mounted, a discharge head mounted upon said tubular air passage having a mixture outlet substantially aligned with the nozzle and formed with an air heating chamber, means for adjusting said nozzle to or from said mixture outlet, means for delivering air through said air heating chamber to said air passage, and means for delivering fluid fuel to said nozzle and for preheating said fuel by means of the heated air drawn from said air heating chamber.

2. A hydrocarbon burner comprising a tubular fluid fuel nozzle having a discharge head at one end and having a semi-tubular portion cut away and a rack of gear teeth

formed upon the edges of the remaining semi-tubular portion, a tubular air passage in which said nozzle is mounted, said passage having a mixture outlet substantially aligned with the nozzle, a tubular fluid fuel passage within which said cut-away portion of the nozzle is located, a gear engaging said rack within said fluid fuel passage, and means exterior to said passage for actuating said gear. 75

3. A hydrocarbon burner comprising a head having a mixture outlet, means for delivering air and fluid fuel to said outlet, means for varying the proportions in which the air and fluid fuel are delivered to said outlet, an air tube mounted in said head discharging adjacent the point of combustion, and means for adjusting said tube to or from the combustion point. 80

4. A hydrocarbon burner comprising a head having a mixture outlet, means for delivering air and fluid fuel to said outlet, means for varying the proportions in which the air and fluid fuel are delivered to said outlet, an air tube slidably mounted in said head at an inclination to the axis of discharge, the outlet of said tube being adjacent the point of combustion, and means for adjusting said tube longitudinally to vary the distance of its outlet from the combustion point. 90

5. A hydrocarbon burner comprising a head having a mixture outlet, means for delivering air and fluid fuel to said outlet, means for varying the proportions in which the air and fluid fuel are delivered to said outlet, a plurality of air tubes mounted in said head and similarly inclined to the axis of discharge, the outlets of said tubes being adjacent the point of combustion, and a common means for adjusting said tubes to vary the distance of their outlets from the combustion point. 100

6. In a hydrocarbon burner, the combination with a discharge head having a mixture outlet, a tubular air passage connected to said head and communicating with said outlet, a fluid fuel nozzle extending within said passage and discharging toward said outlet, means for adjusting said nozzle and discharge head relatively to vary the distance of the nozzle from said outlet, a plurality of air tubes slidably mounted in said head at a similar inclination to the axis of discharge of the nozzle, the outlets of said tubes being adjacent the point of combustion, and an actuating nut adjustably mounted upon said air passage and engaging said air tubes to adjust the same longitudinally in unison. 110

7. A hydrocarbon burner comprising a head having a fluid fuel outlet, a plurality of air tubes mounted in said head and similarly inclined to the axis of discharge, the outlets of said tubes being adjacent the 120

point of combustion, and a common means for adjusting said tubes to vary the distance of their outlets from the combustion points.

5 8. A hydrocarbon burner comprising a head having a fluid fuel outlet, an air tube slidably mounted in said head at an inclination to the axis of discharge, the outlet

of said tube being adjacent the point of combustion, and means for adjusting said tube longitudinally to vary the distance of its outlet from the combustion point.

In testimony whereof I sign this specification.

WILLIAM EGLE.
